UNITED STATES PATENT OFFICE.

HERSCHEL B. BAKER, OF PLAINVILLE, CONNECTICUT.

DESIGN FOR A WATCH OR CLOCK STAND.

SPECIFICATION forming part of Design No. 12,475, dated September 20, 1881.

Application filed August 15, 1881. Term of patent 3½ years.

To all whom it may concern:

Be it known that I, HERSCHEL B. BAKER, a citizen of the United States, residing at Plainville, in the county of Hartford and State of Connecticut, have invented and produced a new and original Design for a Watch or Clock Stand, of which the following is a specification, reference being had to the accompanying drawings, forming part thereof.

10 Figure 1 is a front elevation of my newly-designed stand. Fig. 2 is a like view of the same, showing a slightly-modified form of base, also a watch as hung upon said stand.

15 The leading feature of my design consists in the representation of a stump or butt of a log and branch or branches curved around the space designed for the watch or clock.

20 A designates the base, which I prefer to make in the form of a representation of a stump or 25 the lower part of the body of a tree, and it may be made so as to represent the body of the tree or stump merely, as shown in Fig. 1, or so as to show more of the roots and ground, as represented in Fig. 2. Above the base A a branch, 25 a, extends to the left and curves upward, as

shown, and to the right another branch or trunk, B, having parts of smaller branches thereon, extends and curves upward in such manner as to partially (or, if desired, wholly) inclose a circular space, which is designed for 30 the reception of the watch or clock.

In Fig. 2 I have represented a watch as mounted upon said stand within the circular space, and with the watch-ring hanging on the upwardly-projecting branch b.

35 It will readily be seen that the details of the design—as, for instance, the number and direction of the smaller branches—may be changed without departing from the leading feature, as hereinbefore set forth.

40 I claim—

The design for a watch or clock stand herein shown and described, the same consisting of the representation of a stump or butt of a log and branches curved around the space designed for the watch or clock.

45 HERSCHEL B. BAKER.
